1 Claim

ABSTRACT OF THE DISCLOSURE

A pillow comprises two compartments each being about one-half the pillow height. One compartment contains down feathers and the other contains resilient uncrushed feathers. There are two different ticking materials, one constituting the outer ply of each compartment.

This invention relates to improvements in pillows.

It is an object of this invention to provide a pillow having a filling of a soft layer of fluffy down feathers and a filling of a firm layer of resilient small feathers, the two layers being superimposed and separated by a thin ply of fabric so that the filling of each layer is in its own compartment. There is thus provided a pillow in which each side has a different firmness so that a user can select the desired firmness as a headrest.

It is a further object of this invention to provide a pillow of the type stated in which there are two different ticking materials having different textures, one ticking constituting the outer ply for each layer so that the filling material of the layer can be identified by the texture of the ticking.

The attainment of the above and further objects of this invention will be apparent from the following detailed description taken in conjunction with the accompanying drawing forming a part thereof.

In the drawing:

FIG. 1 is a perspective view of one type of pillow constructed in accordance with and embodying the present invention;

FIG. 2 is a sectional view, on an enlarged scale, taken along line 2—2 of FIG. 1; and

FIG. 3 is an enlarged sectional view of a portion of FIG. 2 in the region of the marginal seam of the pillow.

Referring in more detail to the drawing, 1 designates a pillow comprising outer plies of ticking 2, 3 and intermediate plies 4 of muslin or like material. The plies 2, 3, 4 are superimposed and are marginally secured together throughout their peripheries by suitable stitching. Except for a portion along one transverse edge of the pillow, the stitching is a hidden stitch 6. The stitching also secures the ends of a strip of ticking material 7 that is wrapped around a peripheral bead 8 so that the pillow presents a beaded edge.

The intermediate ply 4 forms with the ticking plies 2, 3 separate filling compartments 10, 11. The compartments 10, 11, when filled, thus provide separate pillow layers with each layer being substantially one-half of the thickness of the pillow. The filling materials in the two compartments are dissimilar such that one of the pillow layers is firmer than the other. Furthermore, the material of

2

the ticking ply 2 has a different texture from that of the ticking ply 3.

In a preferred form of the invention, the filling material in the compartment 10 may be down feathers and the filling material in the compartment 11 may be whole feathers, uncrushed, which are coarser than the down feathers. The ticking material 2 may be down-proof linen-finish ticking cotton of a thread count of 104 x 76. The ticking material 3 may be 8 ounce/square yard cotton sateen.

The pillow 1 may be constructed in a known manner as by superimposing the three panels 2, 3, 4 and the ticking-wrapped bead 8, then securing the pieces together by the stitch 6 so as to leave an unsewn portion along a part 15 of one transverse side of the pillow-bag assembly. Then the assembly is turned inside out. The compartments are then filled with their respective filling materials through the openings of the unsewn portion. The openings are then closed by exposed stitching 12 through the plies and the wrapper-ticking 7.

The precise construction herein shown is merely illustrative of the principles of the invention. What is considered new and sought to be secured by Letters Patent is:

1. A pillow comprising three superposed plies stitched together by stitching that extends through the plies and throughout the perimeters thereof but leaves an unsewn portion, thereby providing an assembly that is subsequently turned inside out to produce a pillow bag with two outer plies and an intermediate ply and in which said bag 25 can be filled through the openings at said unsewn portion and wherein said stitching is hidden within said bag, and separate stitching closing said unsewn portion, the two outer plies being of ticking material, the intermediate ply forming with one outer ply one compartment and forming 30 with the other outer ply another compartment, each compartment containing resilient pillow filling material and with the pillow filling material in each compartment being the same throughout that compartment, the filling material in each compartment being kept separate from the filling material in the other compartment by said intermediate ply thereby to form two discrete pillow layers, and the filling material in one of the compartments being 35 of down feathers and the filling material in the other compartment being whole feathers that are coarser than down feathers so that one layer is firmer than the other layer, one of said ticking plies being a down-proof linen-finish ticking and the other of said ticking plies being a sateen-finish ticking so the filling material adjacent to 40 each ticking ply can be identified by the texture of the ticking plies.
